UNITED STATES PATENT OFFICE

2,584,088

DOOR LOCK

William Floyd, New York, N. Y.

Application October 17, 1949, Serial No. 121,721

4 Claims. (Cl. 292—33)

1

This invention comprises novel and useful improvements in a door lock and more specifically pertains to a mechanism for simultaneously latching a door at a plurality of points, which mechanism is combined with a door latch.

The principal object of this invention resides in providing an improved construction of mechanism for securely latching a door at a plurality of points about its edges; in providing improved mechanism for imparting straight line motion to each of the locking bars or latches; in providing a compact centrally disposed control mechanism for simultaneously operating all of the latching means; in compactly combining the latch control means with the customary door knob and its latch; in providing a locking mechanism which may be readily applied to existing types of doors and door jambs.

Further important objects of the invention reside in providing an improved locking mechanism for a door which shall greatly improve the security of the door fastening means by simultaneously locking the door at a plurality of spaced points about its periphery under the control of a single locking and unlocking mechanism.

These, together with various ancillary objects of the invention which will later become apparent as the following description proceeds, are attained by this device, a preferred embodiment of which has been illustrated by way of example only in the attached drawings, wherein:

Figure 1 is a front elevational view, taken from the inside of a door, showing the manner of applying the invention to a door and door jamb, certain concealed parts being indicated by dotted lines;

Figure 2 is a front elevational view of the leading or opening edge of the door showing the mechanism applied thereto;

Figure 3 is a front elevational view of the door jamb showing the latch retainers applied thereto in accordance with this invention;

Figure 4 is a vertical transverse sectional view through a portion of a door and the locking mechanism applied thereto;

Figure 5 is a vertical longitudinal sectional view showing the interior mechanism of the locking means, and this taken upon the plane of the section line 5—5 of Figure 4;

Figure 6 is an exploded perspective view showing in disassembled position the various component parts contained within the housing of the locking mechanism;

Figure 7 is a detail view in vertical section, taken upon the plane of the section line 7—7 of

2

Figure 4, showing the spring means for biasing the locking mechanism into its locking and releasing position;

Figure 8 is a vertical transverse sectional view taken through one of the latch means in the front edge of the door;

Figure 9 is a side elevational view of the latching means shown in Figure 8, the cover plate thereof being removed;

10 Figure 10 is an exploded perspective view of one of the latches, its operating pinion and crank;

Figure 11 is an assembly perspective view showing a portion of the rear edge of a door and the associated jamb together with the latch and keeper associated therewith; and

15 Figure 12 is an enlarged detail view in vertical section of the latch mechanism shown in Figure 11.

Referring now more specifically to the attached drawings, wherein like numerals indicate similar parts through the various views, 10 designates generally a door which is shown hinged as at 12 to a rear door jamb 14 and associated with a front door jamb 16.

20 Associated with the door 10 and the jambs 14 and 16 is the locking mechanism forming the subject of this invention, and comprising a lock casing 18 which may be secured to the door in any suitable manner such as by fastening screws 20 extending through ears 22 carried by the lock casing. Although the lock casing is shown as detachably bolted to the inner surface of the door 10, it will be readily understood that the principles of this invention contemplate other mountings, such as for example recessing the lock casing 18 within a cavity in the door.

As indicated by the dotted lines shown in Figure 1, the front edge of the door has embedded or recessed therein a pair of latch or bolt casings indicated at 24 and 26, while the rear edge of the door is provided with a similarly recessed bolt casing 28. The door jambs 14 and 16 are provided with keeper means cooperating with each of these bolt casings.

45 Referring now more specifically to Figure 4, and also with reference to Figures 5 and 6, it will be evident that the casing 18 comprises a generally rectangular box having detachable front and rear walls 30 and 32, respectively, secured as by screws 34 to the casing. Journaled in these walls and rotatably received in a bore extending through the door 10, is a shaft 36 which is provided with a keyway 38 adjacent one end thereof 55 for the reception of a key 40, while an operating

knob 42 is suitably secured to the end of the shaft for rotating the same as set forth hereinafter.

The extremity of the shaft 36 opposite from the knob 42 is suitably connected to a key controlled locking cylinder 44 of any suitable type which is mounted in a recess in the outer face of the door 10 in accordance with conventional practice. This locking cylinder is intended to fasten the locking mechanism in its latched or released positions selectively.

As shown best in Figures 4 and 7, the shaft 36 adjacent the plate 30 is provided with a pair of apertured ears 46 which are pivotally engaged by a guide pin 48 whose upper extremity is loosely slideable through an aperture 50 in a lug 52 extending laterally from the plate 30. A coil spring 56 is seated between the ears 46 and the lug 54, and surrounds the rod 50, to yieldingly bias the shaft 36 toward a position on either side of its dead-center position as shown in Figure 7. This spring means, therefore, urges the shaft 36 into selective positions to engage the latching instrumentalities or to release the same, when the shaft 36 has been turned past its dead-center position in either direction.

A generally rectangular plate 58 which may comprise the main bolt of the locking mechanism is slidably received in the casing 18 in upper and lower guides formed between integral longitudinal ribs 60 of the top and bottom walls of the casing 18, and laterally extending longitudinal shoulders upon flanges 62 of the plate 30. As shown best in Figures 4, 6 and 5, the lock member 58 is provided with a transverse, vertically disposed elongated slot 64 through which the shaft 36 extends, and which slot is operatively engaged by a cam or eccentric member 66 slidably received upon the key 40. The arrangement is such that when the shaft 36 is rotated by the knob 42, the cam or eccentric 66 will engage the walls of the slot 64, and advance or retract the lock 58 as desired.

Keyed upon the shaft 36 by means of the above mentioned key 40, are a pair of latch actuating eccentrics 68 and 70 which are respectively adapted to actuate the latches disposed at the front edge of the door and that disposed at the rear edge thereof.

Suitable spacer washers 73 are disposed between the members 66, 68 and 70 and upon the outside thereof, for properly spacing the associated parts in a compact manner.

As clearly set forth in Figures 6 and 5, the eccentric 70 is encircled by an eccentric strap 72 which is detachably secured as by a pin 74 with a rearwardly extending actuating rod 76 which passes through an aperture 78 in the back of the casing 18 and extends thence to actuate the rear bolt as indicated in Figure 1.

The eccentric 68 is surrounded by an eccentric strap 80 to which is pivotally connected as by a pin 82, a vertically and upwardly extending actuating rod 84 which passes through an aperture 86 in the top wall of the casing 18, and thence extends into operative engagement with the upper locking means 24 on the front edge of the door.

As shown best in Figure 6, a vertically disposed lower actuating rod 88 is slidably disposed in aligned apertures 90 in the upper and lower walls of the casing 18, in a manner parallel to the rod 84, and at its upper extremity is provided with a laterally disposed arm 92 which encircles the rod 84 and is secured thereto as at 94, whereby the eccentric 68 will simultaneously operate in

a vertical reciprocation the rods 84 and 88 for simultaneously operating the upper and lower locking means 24 and 26 disposed at the front edge of the door.

As so far described, it will be seen that when the key operated locking means 44 is released, the knob 42 is free to rotate the shaft 36, thereby simultaneously operating the latch rods 84, 88 and 76 as well as the main latching bolt 58. The spring 56 as above mentioned, biases this mechanism selectively into the locked or unlocked position as the shaft passes its dead-center position with respect to the spring.

Attention is now directed more specifically to Figures 1, 11 and 12 for a better understanding of the bolt mechanism 28 at the rear edge of the door.

As shown best in Figure 12, the rear edge of the door preferably adjacent its mid-point, is provided with a mortise 94 within which is received a lock casing 96 secured in any suitable manner, which latter slidably receives a locking bolt 98. Registering elongated slots 100 and 102 are provided in the inner surface of the door 10 and the casing 96 for slidably receiving a bolt or other fastening means 104 whose inner extremity screw-threadedly engages the locking bolt 98 and whose headed outer end extends through an eye 106 formed on the end of the above mentioned actuating rod 76. In the door jamb 14 is appropriately formed a keeper recess or socket wherein is inserted a keeper 108 for receiving the end of the locking bolt 98 when the latter is advanced into locking position by the actuating rod 76 in the manner above mentioned.

Attention is next directed to Figures 8 and 9 in conjunction with Figure 1 for a better understanding of the upper and lower locking bolts of the front edge of the door. Since the locking casings 24 and 26 and their enclosed mechanisms are identical, the showing and description of Figures 8 and 9 will suffice for each. Mortised or recessed into the front edge of the door in each of the upper and lower positions shown in Figure 2, are bolt housings, that of 24 being indicated in Figures 8 and 9. The housing 24 is of generally rectangular shape having side walls to which is detachably secured a cover plate 110 as by means of fastening screws 112.

Rotatably journaled in the housing 24 is a stub shaft 114 whose outer extremity has a lever arm 116 secured thereto as by a set screw 118. The outermost extremity of the arm 116 is provided with an aperture 120 for engagement by one of the actuating rods 84 or 88 above mentioned. At its inner extremity, the stub shaft 114 is provided with a squared or splined portion 122 adapted to non-rotatably receive the hub of a gear 124 which is in mesh with the rack teeth 126 of a latching bar 128. The stub shaft, pinion and latching bar are shown in detail in the composite perspective view of Figure 10. As shown in Figure 9, the latch bar 128 is guidingly and slidably received in a longitudinally extending channel 130, while the pinion 124 is received in a recess 132 opening downwardly from the guiding channel 130.

As shown in Figure 8, the upwardly extending actuating arm 84 pivotally engages the aperture 120 of the lever 116, of the upper latching mechanism 24, while the downwardly extending actuating rod 88 similarly engages aperture 120 of lever 116 of the lowermost latching housing 26.

As shown best in Figure 3, the door jamb 14

at the front edge of the door is provided with suitable keeper and retainer means for receiving the latch bars 126 of the latching mechanisms 24 and 26 and the main locking bar 58 of the housing 18. Preferably, a single keeper strip 134 is secured to the jamb 16 as by fastening screws 136, this retaining strip being provided with recesses 138 and 140 to receive respectively the latching bars of the upper and lower latching members 24 and 26. Intermediate its ends, the keeper plate 134 is provided with an additional keeper 142 provided with a longitudinally extending slot 144 adapted to receive the main latching bar 58, this plate being retained as by fastening means 146.

From the foregoing, the operation of the device will be readily understood and further explanation is deemed to be unnecessary.

Since numerous modifications will readily occur to those skilled in the art after a consideration of the foregoing specification and accompanying drawings, it is not intended to limit the invention to the exact construction shown and described, but all suitable modifications and equivalents may be resorted to falling within the scope of the appended claims.

What is claimed as new is:

1. In a locking assembly for a door having front and rear door jambs comprising a locking mechanism mounted upon the door at the front edge thereof, a casing for said locking mechanism, said assembly comprising a plurality of bolt housings adapted to be mounted upon the door at the front and rear edges thereof, bolt keepers adapted to be mounted in the front and rear door jambs, a lock shaft in said casing, a first cam on said shaft, a main latch in said casing connected to said first cam, a pair of bolts in a pair of bolt housings at the front edge of the door, a second cam on said shaft, means connecting

said pair of bolts at the front edge of the door to said second cam, bolt actuating mechanisms for said pair of bolts, a third cam on said shaft, and means connecting a bolt at the rear edge of said door to said third cam.

2. The combination of claim 1 wherein said main latch comprises a horizontally slidable plate surrounding said first cam.

3. The combination of claim 1 wherein said first mentioned connecting means comprises a pair of parallel vertically slidable rods, one of said rods embracing said second cam, the other rod being connected to said first rod.

4. The combination of claim 1 wherein said first connecting means includes parallel upper and lower vertical rods, the upper rod being connected to said second cam, the lower rod being connected to said upper rod above said second cam and locking mechanism, and means operatively connecting the opposite ends of the rods to said bolt actuating mechanisms.

WILLIAM FLOYD.
